UNITED STATES PATENT OFFICE

JOHN FRANCIS BOORAEM AND EDWARD J. HATTON, OF GREENWICH, CONNECTICUT

FURNACE STRUCTURE

Application filed May 6, 1927. Serial No. 189,424.

This invention relates to furnace structures, and has for its primary object and purpose to provide an improved wall structure for the furnace whereby the part of the 5 wall structure which is exposed to the high temperature products of combustion will be maintained at a comparatively low temperature, and the heat radiated therefrom utilized for the purpose of supplying pre- 10 heated air of high oxygen content to the combustion chamber whereby ignition of the fuel may be facilitated and its more perfect combustion assured.

More particularly, our present invention 15 involves a furnace structure having a main outer wall and a structurally independent inner lining wall composed of courses of refractory blocks, said blocks being constructed and relatively arranged in the ad- 20 jacent courses so as to provide throughout the area of the wall a multiplicity of ver- tically and horizontally extending intercom- 25 municating air circulating passages. Suitable provision is made in the outer main wall for admitting the cool external air to 30 said circulating passages and at suitably predetermined points the inner lining wall is also provided with means for admitting the air from said circulating passages into the combustion chamber of the furnace. Owing to the fact that the refractory blocks 35 of the inner lining wall are not interlocked or bound to the bricks of the outer wall, under the intense heat generated in the com- bustion chamber, the lining wall blocks may expand without resistance, thus obviating fracture or breakage thereof. By our im- 40 proved construction and arrangement of the blocks in the lining wall, we obtain a maxi- 45 mum area of each block with which the air may contact whereby the heat absorbed by refractory blocks maintained at a compara- off by the circulating air currents and said refractory blocks maintained at a compara- 50 tively low and substantially uniform tem- perature.

It is also an additional object of our in- 55 vention to provide an improved arrangement of the bricks in the outer main wall of the 50 furnace structure which will result in an

equalization of expansion of the wall throughout its area and tend to obviate the formation of breaks or crevices at the joints thereof.

With the above and other objects in view, 55 the invention consists in the improved fur- nace structure and in the form, construction and relative arrangement of its several parts as will be hereinafter more fully described, 60 illustrated in the accompanying drawings 60 and subsequently incorporated in the sub-joined claims.

In the drawings, wherein we have shown one simple and practical embodiment of the invention, and in which similar reference 65 characters designate corresponding parts throughout the several views,—

Figure 1 is a vertical sectional view of a part of one of the side walls and the bottom or floor of the furnace structure showing one 70 embodiment of our present improvements;

Fig. 2 is a detail perspective view of one of the refractory blocks of the inner lining wall of the furnace;

Fig. 3 is a fragmentary inner face view 75 of the lining wall;

Fig. 4 is a horizontal sectional view taken substantially on the line 4—4 of Fig. 3;

Fig. 5 is a vertical sectional view taken on the line 5—5 of Fig. 4;

Fig. 6 is a similar vertical section taken on the line 6—6 of Fig. 4;

Fig. 7 is a fragmentary elevation of the outer side of the lining wall of the furnace;

Fig. 8 is a detail vertical section showing 85 a slightly modified application of our pres- ent improvements, and

Fig. 9 is an interior fragmentary elevation as indicated by the line 9—9 in Fig. 8.

It will be understood as this description 90 proceeds that our present improvements may be applied only to one of the furnace walls, or to both of the side walls and also to the rear and bottom wall or floor of the furnace structure as may be desired. Pref- 95 erably, the structure embodies an outer main wall generally indicated at 5 which may be composed of ordinary building brick. These brick are desirably arranged in super- 100 imposed courses in the manner illustrated

more particularly in Figs. 5 and 6 of the drawings, from which it will be observed that the bricks are arranged in two superimposed stretcher courses 6, said wall having a thickness equal to three of the stretcher course bricks. Each brick is of a length substantially equal to twice the width thereof, and above each two courses of the stretcher brick 6, a course of header brick 7 are arranged, the outer ends of said header brick being flush with the outer face of the wall. At the inner ends of these header bricks 7, a single course of stretcher brick 8 are arranged in line with the inner bricks of the stretcher courses 6. Between each pair of courses of the stretcher bricks 6 and the bricks 7 and 8, a course of header bricks 9 is arranged with their inner ends flush with the inner face of the wall 5 and a course of stretcher brick 10 extends between the outer ends of the header bricks 7 and the outer stretcher course bricks 6. This distribution of the bricks composing the outer main wall of the furnace more effectively breaks up and equalizes the forces of expansion throughout the wall structure and obviates breaking of the joints at the outer face of the wall.

The inner lining wall 11 of the furnace structure is composed of courses of refractory blocks, one of which is shown in detail in Fig. 2 of the drawings. These blocks are comparatively large and are formed in a suitable mold to provide a rectangular body section 12 upon one side of which and centrally thereof a projection or extension 13 is formed, the end portion of the extension being reduced in thickness or provided at its upper and lower faces with the rabbets or open channels indicated at 14. Preferably, the side face of the body 12 of the block where it merges or joins with the end faces of the projection 13 is arcuately curved as indicated at 15.

From the above description it will be understood that the inner face of the outer wall 5 is entirely smooth or unbroken. In erecting the inner refractory lining wall, the blocks are arranged in superimposed courses as clearly shown in Figs. 1 and 3 of the drawings with the end joints between the blocks in each course horizontally spaced from the end joints between the blocks of the adjacent upper and lower courses for a distance substantially equal to one-third of the length of the block. By this arrangement, the ends of the projections 13 on the refractory blocks in adjacent courses which are engaged against the inner face of the outer main wall 5 are laterally spaced apart, thus producing as shown in Figs. 4 and 7 of the drawings, substantially vertically continuous channels or air passages 16. These passages are of course, in open communication with the spaces between the projections

13 of the refractory blocks in the same course and the overlapping ends of these projections on the blocks in adjacent courses being provided with the rabbets or channels 14, thus provide horizontal communicating passages between the vertical air passages 16. Therefore, it will be understood that there may be a free circulation of air both vertically and horizontally between the outer wall and the inner refractory lining and in contact with the surfaces of the refractory wall blocks.

At suitable intervals in the main outer wall 5, openings are provided in communication with spaces between the projections 13 of adjacent refractory blocks of the inner lining wall so that the external air may be drawn into the circulation passages between the inner and outer walls by the induction effect created through said passages by the natural draft of the furnace. Therefore, I provide certain of the refractory lining wall blocks with openings or recesses also communicating with the air passages and through which the preheated air is drawn into the combustion chamber. As herein shown, we preferably provide the refractory blocks at one of their ends and in one of the longitudinal faces thereof with the transverse recesses 17, said blocks when arranged in adjacent courses of the wall having the recesses 17 thereof in mating or registering relation as clearly shown in Fig. 3 of the drawings. However, any other desired arrangement of these air inlet openings through the inner lining wall may be provided.

In Fig. 1 of the drawings, we have also shown the floor or bottom of the combustion chamber having an upper section composed of refractory blocks. In such case however, the blocks 12' are of less thickness than the refractory blocks used in the side walls of the furnace. Otherwise, their construction and arrangement is similar to that above described so as to provide intercommunicating passages between said blocks and the underlying base wall of masonry or other material which extend both longitudinally and transversely of the combustion chamber and at suitable intervals communicate with the latter through openings formed in the refractory blocks. It will be noted that the rows of blocks 12' contiguous to the side and end walls of the furnace, may extend under the lowermost courses of fire blocks of the latter walls so that the air circulation passages of said walls and of the floor of the furnace will be in communication with each other.

In Figs. 8 and 9 we have illustrated another alternative arrangement which may be used in conjunction with a masonry or concrete furnace wall structure for the purpose of supplying preheated air beneath the fuel bed supporting grate of the furnace. In

this case, immediately above the grate, the inner face of the furnace wall is provided with a channel or recess 18 of suitable depth and width which is adapted to receive the two rows of refractory blocks 12^a of the construction above described. Air supply openings 17^a extend through the furnace wall from the outer face thereof and supply air to the passages formed between the spaced projections 13 of the refractory blocks in the upper row. The spaces between the projections on the blocks 12^a in the lower row communicate with the interior of the furnace below the grate 20 through additional passages 19 formed in the wall structure. Thus, the air entering through passages 18 will be pre-heated by contact with the refractory blocks 12^a before it is admitted through the passages 19 and is drawn upwardly through the fuel bed, thus facilitating the rapid combustion of the fuel.

From the foregoing description considered in connection with the accompanying drawings, the construction, manner of operation and several advantages of our present improvements will be clearly understood. It will be seen that there is no bond or positive connection of any kind between the inner refractory lining wall and the main outer wall of the furnace structure so that the blocks or units composing said lining wall are free to expand with respect to the outer wall. It will also be apparent that we thereby obtain a maximum surface area on each of the refractory blocks with which the air entering between the inner and outer walls may come into contact. Therefore, the air circulating between said walls will rapidly absorb heat radiated from the refractory blocks to maintain the same at a substantially uniform and comparatively low temperature. Since this air circulated between the walls becomes thus highly heated, it may if desired, be utilized for combustion purposes in furnaces of the type burning pulverized fuel, oil or gas by discharging the preheated air into the furnace at the zone of combustion either by induced draft or under pressure of a suitable blower. Therefore, it will be appreciated that our invention provides not only for a furnace structure which will not rapidly deteriorate or burn out and require frequent relining of the walls, but also provides a means whereby more perfect and thorough combustion of the fuel may be obtained, thus resulting in economical operation of the furnace.

While we have herein shown and described several simple and desirable embodiments of our present improvements, it will nevertheless be understood that the essential features thereof might also be embodied in various other alternative structures, and we accordingly reserve the privilege of resorting to all such legitimate changes therein

as may be fairly embodied within the spirit and scope of the invention as claimed.

We claim:

1. A furnace lining wall composed of refractory blocks each having an elongated rectangular body portion and a part projecting centrally from one side of said body portion for a distance substantially equal to the thickness of the body portion of the block, said part being substantially square in cross section and adapted for abutting contact against the inner face of the furnace wall, said blocks being arranged in horizontal courses, and the spaces between said projecting parts of adjacent blocks providing air passages therebetween of substantially equal area to the area of contact of said parts with the face of the main furnace wall. 70 75 80

2. A furnace lining wall composed of refractory blocks each having an elongated rectangular body portion and a part projecting centrally from one side of said body portion for a distance substantially equal to the thickness of the body portion of the block, said part being substantially square in cross section and adapted for abutting contact against the inner face of the furnace wall, said blocks being arranged in horizontal courses, and the spaces between said projecting parts of adjacent blocks providing air 85 90 95 100 105 110 115 120 125 130

passages therebetween of substantially equal area to the area of contact of said parts with the face of the main furnace wall, and said projecting part of the block being provided at the end thereof and in its upper and lower faces with horizontally extending channels, said channels in the blocks of the vertically superposed courses adapted to register to form horizontally extending connecting passages between said air spaces.

In testimony that we claim the foregoing as our invention, we have signed our names hereto.

JOHN FRANCIS BOORAEM.
EDWARD J. HATTON.
